HIGH AIR CAPACITY SELF-PRIMING PUMP

Harry E. La Bour, Elkhart, Ind.

Application November 10, 1939, Serial No. 303,718

6 Claims. (Cl. 103—113)

The present invention relates to self-priming centrifugal pumps and the principal object of the invention is to provide means for rendering a self-priming centrifugal pump of the air-entrainment liquid-recirculating type capable of rapid removal of air from the suction side of the pump throughout the entire range of suction of which it is capable.

While I have shown herein a specific embodiment of the invention, this is by way of illustration rather than limitation. The principle herein disclosed may be embodied in a wide variety of centrifugal pumps, including the concentric type, the volute type, the turbine type, and others. The shaft of the pump may be horizontal or vertical without departure from the invention.

From observation and experiments, I have determined that in the operation of a self-priming centrifugal pump utilizing the entrainment-recirculation principle, there is an optimum value of the fluid recirculated for producing a maximum rate of gas removal, other things being equal. The stream of fluid going through the pump should be of a certain cross section independently of tip velocity or of suction prevailing in the casing. If too little liquid relative to the size of the pump is recirculated the effectiveness of air removal suffers for lack of sufficient volume of entraining and carrying medium. If the recirculation stream is so small relative to the physical dimensions of the pump that the flow of fluid fails to fill the discharge throat where kinetic energy is developed into pressure, the operation is unsatisfactory. On the other hand, if the recirculated stream is more than enough to fill the discharge throat, the operation involves not only idle movement of liquid but results in actual interference with the formation and discharge of a proper mixture of gas and liquid. In other words, there must be sufficient liquid to provide a full discharge of the mixture, and, at the same time, there must be the proper gas to liquid ratio. On the other hand, there must not be so much liquid in the circulation as to produce overfilling of the impeller and discharge, nor to produce a gas to liquid ratio which is too low. The present invention aims to control the size of the recirculation stream whereby to obtain rapid air removal.

Various forms of self-priming centrifugal pumps are now on the market. One of the best known forms is that involving the use of the so-called hydraulic balance to prevent excessive return of water to the pump casing under the higher vacuums. This pump is shown in my Patent 55

No. 1,578,236, and a specific form of throating commercially employed is shown in my Patent No. 2,163,951. According to the principle of that pump, the liquid during recirculation is brought into the impeller chamber at or near the periphery of the impeller.

This system and method of operation has been highly successful, but it has one deficiency. As in the case of all other self-priming pumps which obtain their air-handling capacity by entrainment, that is, mixing the liquid and the gas, the amount of gas which can be removed is a factor of the carrying vehicle or liquid available for mixing. At the start of the priming cycle of the 15 hydraulic balance type of pump there is no force but gravity to bring the liquid into the impeller, and this is counteracted by the action of the impeller blades so that until some appreciable vacuum is developed at the eye of the impeller the amount of water returned into the impeller is relatively small. The amount of water returned increases as the vacuum increases up to a point where the maximum desirable flow is reached, and from then on the hydraulic balance effect 20 functions to prevent the reentry of further liquid. The difficulty in getting water back into the impeller under low vacuum conditions materially retards the priming speed.

Another scheme which is in common use provides for the return and recirculation of liquid 30 from the separator back to the suction side of the impeller. This general scheme may be divided into several sub-classifications, the shortcomings of which will be pointed out below.

35 The simplest arrangement is a connection between the separator and the pump suction, which connection is wide open at all times, but is restricted in size so as to limit the amount of liquid which can be returned. Since the direction of 40 flow is always the same, and since the amount of liquid returned from the discharge back to the suction is in direct proportion to the difference in pressures, it is obvious that after prime has been completed the rate of flow back to the suction is greatest, and inversely, when the cycle starts, the rate of flow is the least. The pump is therefore seriously limited by the fact that the size of the by-pass must be quite small to prevent excessive loss of liquid during pumping 45 operation, but it should be quite large during priming to allow return of an adequate flow of priming liquid. Hence this arrangement is probably the poorest method of self-priming now in use.

Another scheme provides for a controlling

valve in the by-pass. The actuating element of this valve is located in the stream of discharge liquid, and the impact of discharge operates to close the valve covering the by-pass opening. Since the valve actuator is operated by impact, its operation depends mainly upon the velocity of liquid in the discharge throat. Since the velocity of discharge is not a measure of the quantity of liquid utilized as a priming vehicle, the scheme does not give a satisfactory control. Impact is, of course, dependent upon mass, which is a function of volume and density, and upon the square of the velocity. Since the velocity is the overpowering factor and since it is not related to volume, the control is imperfect. At the very outset of operation the by-pass valve may be wide open, and could thus, theoretically, admit a sufficient amount of liquid to the suction. However, immediately upon starting, assuming the original quantity of liquid returned is adequate, the velocity in the throat also is sufficiently large that choking of the return flow immediately results almost from the initiation of operation. From then on, as suction increases, the control is highly unsatisfactory. This scheme, therefore, does not meet requirements.

A variation of the above scheme involves the insertion of the control element of the valve in the pump suction passageway. This avoids to a considerable extent the difficulty produced by variable velocity, but introduces another difficulty. The only medium capable of actuating this valve is incoming liquid after the prime has been completed. Consequently, there is no control whatsoever of the by-pass until water from the outside source actually enters the pump. As a result, if the by-pass opening is made large enough to meet the starting requirements it very quickly drowns the pump as the vacuum increases. Hence, although a high air capacity may result at extremely low vacuums, the higher vacuums cannot be obtained except by restricting or limiting the size of the by-pass. Consequently this scheme has practically the same shortcomings as an uncontrolled by-pass in so far as the speed of priming is concerned. It has the advantage of shutting off all recirculation after liquid inflow is established, but it does not meet the requirements for high air capacity and high vacuum combined.

A third scheme uses a by-pass from the discharge back to the suction, which by-pass is controlled by a valve operated by pressure in the discharge. This pressure valve remains open at all times until pressure is built up in the separator. Thereupon the pressure valve closes and shuts off the by-pass. This has the same defects as the scheme using the control valve in the suction, but with the added difficulty that pressure must be built up following actual entry of water into the pump.

The problem which confronted me, and which the present invention solved, is the provision of a pump of the self-priming type which will provide a control the same as or equal to that available by the hydraulic balance principle while the vacuums are appreciable, but which will also have the added advantage of quick and ample return of priming liquid when only gravity or a low difference of pressure is available.

I have found by experiment that for a large return of priming water from the separator to the impeller chamber a relatively large opening is necessary. The most feasible place to dispose this opening is between the separator and the

intake of the impeller chamber. To determine the amount of liquid which is to pass through this by-pass, I provide a metering channel which in the preferred embodiment is the main discharge throat of the pump. This may be a main tangential or volute or any other type of throat. The liquid which can pass through this channel is determined by design to be the liquid which is optimum for maximum rate of air removal in the particular pump. Any excess of liquid or mixture of air and liquid within the pump beyond the stream which fills the metering channel is diverted to an overflow channel. This overflow channel may be in the preferred embodiment and is the separate auxiliary discharge passageway of the hydraulic balance type of pump. These two channels need not be physically separated, but their functions are to be made distinguishable by the responsive means. The direction of liquid flow occurring in this overflow channel is a gauge or determination of the adequacy of liquid circulation in the pump itself. I provide a flow control orifice or restriction in the by-pass and I put the control of the effective opening of the flow control orifice or restriction under means which is sensitive to flow in the overflow channel. Thus, by controlling the size of the flow controlling orifice or restriction in accordance with the amount and direction of flow in the overflow channel, it is possible to circulate substantially the exact amount of fluid through the metering channel which corresponds to maximum air handling.

In referring to the metering channel and to the overflow channel I do not intend to imply that these channels must necessarily be separate and independent. The concept involved is that a certain size stream shall flow through the pump and into the separator without effecting any substantial control of the flow control orifice, but when the stream is greater than a certain size the excess shall exert an influence upon closing off the flow control orifice or restriction so that the opening of the flow controlled orifice is reduced to the point where the desired size of flow is established. By using a slot or throat for the discharge of the impeller to the separator which slot or throat is relatively long compared to its width, or is otherwise similarly shaped, the two channels may find place in spaced apart parts of the slot or throat. The flow which will fill a predetermined anterior part of this slot or throat may constitute the permitted size of stream and being substantially ineffective with respect to the vane or other control element that effects or governs closure of the flow control orifice. When the outflow increases to the point of filling the other end of the slot or throat corresponding to a separate overflow channel, the vane or other means for controlling the size of opening of the flow controlling orifice is actuated to reduce the size of said return flow controlling orifice.

When liquid from the outside source begins to enter the pump it makes up a part of the fluid flow through the main metering channel, and the excess which thereupon shows up at the overflow channel acts upon the control orifice to reduce the amount of liquid returned. Thereby any inflow from the outside displaces so much of the return circulation. When sufficient inflow occurs to fill the metering channel and begins to spill over into the overflow channel the bypass is partly or completely cut off by closing partly or

75 completely the flow control orifice or restriction.

This method of operation provides an ample supply of priming water at low suctions and permits a principle of flow control similar to the principle of hydraulic balance to control the operation at the higher suctions, so that substantially optimum conditions for maximum air handling capacity prevail throughout the entire range of suctions in this pump.

The above described method and principle of operation may be embodied in a vertical form of pump as well as in a horizontal pump and the method and principle may be embodied in a pump with a single pair of main and overflow channels, or a plurality of the same. Also this principle of flow control may be combined with the hydraulic balance principle in the same structure.

Now in order to acquaint those skilled in the art with the manner of constructing and operating my invention I shall describe, in conjunction with the accompanying drawing which forms a part of this specification, a specific embodiment of the invention.

In the drawing:

Figure 1 is a vertical diagrammatic cross-section of a pump embodying my invention; and

Figure 2 is a plan view of the same, showing a section through the separator on the line 2—2 of Figure 1.

The pump herein illustrated comprises an intake trap member 1, the pumping chamber 2 and a separator 3. The intake trap 1 is provided with a suitable clamping flange 4 by which it may be connected to a suitable suction pipe leading to a source of liquid at a lower level. Alternatively, it may lead to any other source of fluid which it is necessary to extract by suction. The trap member 1 and the pumping member 2 are joined by mating flanges 5 and 6, respectively. The separator 3, which in this case is shown as lying directly above the pumping chamber 2, is coupled to the pumping chamber by mating flanges 7 and 8 and the separator 3 has a top outlet 9 surrounded by a clamping flange 10 by which it may be connected to a suitable discharge pipe. The trap member 1 includes the trap space 11 and this communicates through a relatively short neck member 14 with the eye of the impeller chamber 12. The separator member 3 has separating space 13 in which gas is permitted to separate from liquid during the operation of the pump, particularly during priming. The intake neck 14, which leads to the pumping casing 2, is connected through a passageway 15 to the bottom part of the separator space 13. The pumping chamber 12, in the specific form illustrated herein, is a concentric chamber, that is, it has a circular wall about the periphery of the impeller 16 which is swept by the impeller blades. The blades operate in a peripheral channel, which peripheral channel communicates with the main throat 17 and its expanding passageway 17'. The throat 17 and passageway 17' constitute in this structure the metering channel. The pumping channel communicates also with an auxiliary throat 18 and its expanding passageway 18', the discharge of both passageways leading to the bottom of the separator space 13. The auxiliary throat 18 and its passageway 18' constitute in this structure the overflow channel. A swinging valve member 19, pivoted at an intermediate point on a horizontal pivot 20, has a valve and vane member 22 overlying and normally closing off the upper end 70 of the expanding passageway 18' of the throat 18. 75

The opposite extremity of the member 19 is an arcuate swinging gate valve 23 which obstructs a concentric port 24. The gate valve member 23 is connected to the main body part of the valve member 19 by the arms 26 which afford a minimum obstruction to flow to liquid from the bottom of the chamber 13 down into the cavity 27 through the port 24 and into the intake of the pumping chamber. The valve 23 is constructed as a gate valve in order to be as little influenced by flow through the port 24 as possible. It should in effect be balanced so that neither flow nor suction materially affect its positioning. In other words, it is to take a neutral position as controlled by the vane and valve member 22 at the opposite end. The vane and valve member 22 is suitably counterbalanced by sufficient weight of metal, or it may be overbalanced by a spring, so that its normal position is such as to close the outlet of the passageway 18'. This vane and valve member 22 is partially housed or shrouded by a vane or wall 28 which forms also a part of the supporting means for the hinge or pivot of the swinging member 19. The member 28 has laterally disposed arms 29, 29 which terminate in clamping lugs 31 by which the member 28 is bolted to the horizontal wall 32, and downwardly extending hinge lugs 33 supporting a hinge pin for the pivot 20 of the member 19.

The impeller shaft 34 is adapted to be operated at substantially a predetermined speed for which the pump is designed.

The size of the port 24 and the passageway 15 for the return of priming water from the separator back into the intake of the pump is, by design, large enough to admit adequate volume of water at the head which will, in practice, prevail in the pump when it is ready to start. The throat 17 and its expanding passageway 17' are designed to be of a size which will permit the right amount of water to be carried in the impeller to produce maximum rate of air entrainment and evacuation from the intake side. This is independent of speed and pressure. The throat 17 and its passageway 17' thereby constitute a metering channel for determining the proper cross section of flow of discharge fluid for optimum rate of air removal. The auxiliary throat 18 and its passageway 18' constitute the overflow channel, flow through which is detected and responded to by the vane 22. This overflow channel has an additional function in that it is designed to constitute a secondary discharge for liquid when the pump is primed and is operating upon liquid. It forms a parallel path for discharge and thereby increases the capacity of the pump to handle liquid. Its size may be designed accordingly.

The trap 11 in a pump embodying this invention need not be as large as on conventional pumps of the hydraulic balance type for the reason that the large bypass 15 will allow air from the discharge, that is, through the trap 11, to pass down through this bypass 15 and fill the suction pipe upon the descent of the column of liquid which drops when the pump stops its action. The vacuum is thus broken without requiring the liquid to be pulled out of the impeller casing.

The impeller 16 may be of any suitable form. I prefer to utilize, in the concentric type of casing, a fairly straight blade the ends of which may be slightly recurved, but this is merely one specific form by way of illustration. Where a volute

type of casing is employed curved blades are preferable. The separator may be directly above the pump or may extend to one side, and, in fact, any suitable arrangement of the parts which secures the novel method of operation may be utilized.

The operation of the pump is as follows: Assuming that the pump has been connected to suction and discharge and a suitable source of liquid provided for the suction, and that the pump body is charged with a charge of priming water which may stand at a suitable level at or a short distance below the bottom of the intake opening 35, the shaft 34 of the impeller 16 is 10 sub-rotated. The valve member 19 stands in substantially the position shown in full lines in Figures 1 and 2 when the shaft 34 starts rotating. Immediately upon initiation of rotation, all the 15 liquid which the impeller can reach will be driven up into the separator space 13 through both throats 17 and 18, temporarily swinging the member 19 in counterclockwise direction to close off the port 24 by means of the gate valve 23. As soon however, as the volume of liquid in the 20 impeller chamber 12 has been reduced to that which will fill only the throat 17 and not discharge through the throat 18, the valve 19 will 25 rotate into clockwise position where the member 22 closes off the top of the passageway 18', preventing the return of liquid through the said 30 passageway 18' but permitting full flow through the port 24 of the bypass 15 into the intake of the pump.

It is assumed that the pump starts without any suction, that is, atmospheric pressure 35 prevails in the trap 11 and in the connected passageway leading to the eye of the impeller. The initial transfer of liquid may very slightly change this pressure relation, but let it be assumed that the only head of liquid causing return flow through the bypass 15 is the head of liquid in the chamber 13. This is a small head, but the throat 15 is large enough to permit adequate return of liquid for filling the throat 17. Air will be entrained at the desired maximum rate and will be carried out through the passageway 17' into the separator space 13 and there the gas escapes upwardly and out of the opening 9, the liquid being retained, and naturally the denser or more gas-free liquid gravitates to the bottom of the chamber 13. Here it returns, and the circulation is thus maintained and air evacuated from the intake side. Evacuation of air from the intake side immediately produces a pressure difference, that is, atmospheric prevailing in the separator and sub-atmospheric prevailing in the intake, whereby the flow of liquid through the bypass 15 is now impelled by an additional force, namely, the pressure difference added to the gravity head. Hence, if the passageway 15 is large enough to permit adequate return flow under the influence of the gravity head alone, it is now too large for optimum gas removal when the added force of pressure difference acts upon the return flow. Therefore, more liquid will return than is desired, that is, more than will fill the throat 17, and some will be carried over into the throat 18. As soon as liquid is carried over into the throat 18 the impact of the same upon the vane and valve member 22 will cause the same to swing in a counterclockwise direction, bringing the gate valve 23 down over the port 24 and reducing the size of the port opening 24. Thereby the flow through the bypass 15 is reduced to the desired degree where

just sufficient excess of liquid over that desired in the throat 17 will flow into the throat 18 and keep adjusting the position of the member 19 to continual throttling of the port 24, which port must be throttled as the pressure difference increases because of the greater velocity of liquid through the port 24, even though it be restricted.

The adjustment of the weight of the member 22 as to loading, whether by counterweight or by additional spring pressure, or other means, controls the amount of excess which must be produced in order to generate the necessary force for closing the valve 23. The movement of the member 22 may be controlled mainly by impact of fluid in the throat 18, or it may be controlled mainly by flow, particularly since the member 22 may be shrouded by the member 28. This member 28 thus performs the dual function of preventing interference of the flow from the throat 17 with the member 22, and also it may serve in conjunction with the swinging vane 22 as a weir or flow restriction to graduate the position of the member 22 for a predetermined flow volume through the throat 18. Thus the stream of mixture which is the optimum stream for maximum rate of air removal is maintained by comparing it with the capacity of the throat 17. If the stream is greater than that which will pass through the throat 17 it will spill over into the throat 18 and thereby further restrict the port opening 24 to maintain substantially a constant cross sectional size of the stream of liquid. This size of the stream is independent of velocity of the stream and independent of the pressure difference between the pressure prevailing in the pocket or separator 13 and the pressure prevailing in the intake side of the pump.

If now, at the prevailing suction, a small amount of liquid should begin to enter the pump through the intake, it would constitute a part of the flow through the throat 17 and to that extent would displace some of the circulating liquid by acting through the swinging member 19 to close off the return port 24. If the inflow gradually increases, this inflow substitutes itself for the circulating medium through the port 24, maintaining air removal at optimum conditions until liquid in sufficient volume flows into the intake to produce a complete closure of the bypass 15, and at that stage the pump by design is capable of operating without the necessity of further recirculation or of removing air without recirculation and continues to discharge liquid through both throats 17 and 18 in parallel, driving the same through the separator and out the discharge opening 9. During normal pumping of liquid after the pump has primed itself the overflow throat 18 becomes an auxiliary discharge throat, increasing the pumping capacity of the pump. If at any time the liquid supply should fail and air should enter the pump, the pump will immediately proceed to the recirculation method above described.

As above explained, the block of metal 35 which produces complete separation of the two passageways 17' and 18' is not essential, and, in fact, if the shape of the discharge opening is suitably designed so that the two functional channels are provided in a single passageway the separation 35 may be omitted. Two separate passageways as shown are more positive and efficient and constitute the preferred form.

The vane member 22 need not completely close off the passageway 18' when in its non-actuated position.

As I have above indicated, the specific details of construction and the mode of arrangement of the parts may be widely varied within my invention, as defined in the appended claims.

I claim:

1. A recirculating gas entraining pump comprising a separator, an impeller and cooperating casing, means providing a main discharge metering channel open at all times from the casing into the separator, means providing an overflow channel out of the casing into the separator, means providing a return flow controlling orifice between the separator and the impeller casing, and means controlled by fluid flow through the overflow channel for reducing the size of the flow controlling orifice.

2. In a self-priming pump of the air entraining liquid recirculating type, an impeller casing containing an impeller channel, and having a main discharge channel for discharging a predetermined flow of fluid mixture, an auxiliary channel intended to operate as a parallel discharge channel when the impeller chamber is supplied with its full complement of liquid, a return conduit for the flow of recirculating liquid into the impeller casing, and a swinging gate valve controlling the flow through the return conduit, said gate valve having a counterpoised vane subject to the flow of fluid through the auxiliary channel for shifting the gate valve.

3. In a self-priming pump of the air entraining recirculating type, an impeller chamber and an impeller therefor, a separator, an intake connection, a bypass from the separator to the intake connection, there being a discharge channel for the discharge of a predetermined flow of fluid mixture out of the impeller chamber into the separator, and an adjacent auxiliary discharge channel for receiving any fluid mixture in excess of said predetermined flow, and means sensitive to a predetermined flow of fluid mixture through said auxiliary discharge channel for diminishing the flow of returning liquid in said bypass.

4. In a device of the class described a pump body comprising an impeller casing having a central inlet connection, an impeller channel, a pair of adjacent tangential discharge passageways communicating with said channel, the anterior one in the direction of rotation of the impeller forming a main passageway and the posterior one forming an auxiliary passageway, a

separator casing providing a separator chamber communicating with said passageways, an intake member providing an intake trap chamber communicating with the intake of the impeller casing, a bypass between the separator and the intake, a valve controlling said bypass, and a flow sensitive element subject to flow in said auxiliary passageway for controlling the position of said valve.

5. In a device of the class described, a pump body comprising an impeller casing having a concentric pumping channel, an impeller working in said channel, there being two substantially adjacent tangential discharge passages comprising a primary passage and a secondary passage, the primary passage being adapted to be filled with the stream of liquid and entrained gas during priming, said primary passage determining the volume of liquid circulation during priming, a separator communicating with said passages, an intake including a trap leading to the eye of the impeller, a bypass between the separator and the intake, a normally open valve controlling said bypass, and means responsive to fluid flow out of said secondary passage controlling the closing of said valve.

6. A self-priming centrifugal pump having an impeller chamber, an impeller working in the chamber, an inlet connection including an intake trap leading to the central part of the impeller chamber, a separator, a bypass from the separator to the intake, said bypass being of a size such as to permit a predetermined stream of liquid to flow by gravity head into the impeller which flow provides substantially the optimum volume of liquid in the impeller chamber for producing substantially the maximum rate of air entrainment and discharge, a valve for reducing the effective opening of the bypass as the suction produced in the impeller chamber increases the head upon the return flow, throating between the peripheral part of the impeller chamber and the separator, said throating including a channel capable of conveying the said predetermined stream of liquid mixed with air and a channel for conveying discharged fluid in excess of said predetermined stream, and means controlled by flow in said second channel for governing the shifting of said valve toward closed position.

HARRY E. LA BOUR.
